US0D1043664S

(12) **United States Design Patent** (10) **Patent No.:** **US D1,043,664 S**
(45) **Date of Patent:** **** Sep. 24, 2024**

(54) **WEARABLE ELECTRONIC DEVICE**

(71) Applicant: **VTech Electronics, Ltd.**, Tai Po (HK)

(72) Inventor: **Cheuk Shing Lin**, Tseung Kwan O Plaza (HK)

(73) Assignee: **VTECH ELECTRONICS, LTD.**, New Territories (HK)

(**) Term: **15 Years**

(21) Appl. No.: **29/744,322**

(22) Filed: **Jul. 28, 2020**

(57) **CLAIM**

The ornamental design for a wearable electronic device, as shown and described.

DESCRIPTION

FIG. 1 is a front perspective view of a wearable electronic device showing my new design;

FIG. 2 is a rear perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The broken lines in the drawings illustrate portions of the wearable electronic device that form no part of the claimed design.
